UNITED STATES PATENT OFFICE.

JOHN A. WILLIAMSON, OF DENVER, COLORADO.

FINGER-GRASPING RAZOR-BLADE HOLDER.

1,378,079.

Specification of Letters Patent.

Patented May 17, 1921.

Application filed June 22, 1920. Serial No. 390,937.

To all whom it may concern:

Be it known that I, JOHN A. WILLIAMSON, a citizen of the United States of America, residing at the city and county of Denver 5 and State of Colorado, have invented a new and useful Finger-Grasping Razor-Blade Holder, of which the following is a specification.

My invention relates to a finger grasping 10 razor blade holder, and the objects of my invention are:

First: to provide a finger grasping razor blade holder in which loose, naked razor blades are instantly inserted in a guide 15 holder in proper position to shave with, and that can be instantly removed from the holder after shaving.

Second: to provide a shaving razor blade holder in which loose, free, razor blades are 20 adjustably and removably clamped, and secured in a finger grasping, naked razor holder.

Third: to provide a simple razor blade renewably holding shaving device, that is 25 simple and practicable in construction, and that can be more quickly and easily and safely drawn over the face and neck than the commonly used handle provided and folding razors.

I attain these objects by the mechanism 30 illustrated in the accompanying drawings, in which—

Figure 1 is a perspective view of a razor constructed in accordance with my invention.

Fig. 2 is a side view of the same, partly in section, and in a reverse position with respect to Fig. 1.

Fig. 3 is a perspective view of a modified form of the holder.

Fig. 4 is a side view of Fig. 3.

Figs. 5 and 6 are side views of holders provided with end stops for holding the razor blade against endwise movement.

Figs. 7 and 8 are side views of holders provided with swinging plates which act in connection with the back plate to hold the razor blade; and

Fig. 9 is a plan view of Fig. 7.

Similar letters of reference refer to similar parts throughout the several views.

My finger grasping razor blade holder comprises loose, naked razor blades of preferably about two inches in length, although 55 they may be made shorter or longer if desired, and a holder for the blades that is

arranged to hold them in a face and neck engaging and shaving angle.

The razor blades that I use, while shorter than those in the jointed handled razors in 60 use, are preferably made of the same shape and thickness and width.

The razor blade guiding holder is a finger grasping plate shaped casing member that supports and almost wholly incloses 65 and safely holds the razor blades at the proper shaving angle, as will be fully illustrated and explained, as follows:

Referring to the drawings, especially 70 Figs. 1 and 2:

The numeral 1, designates the finger grasping portion of my razor blade holder. This casing may be made of any suitable metal or material, but I preferably construct it of thin sheet brass or any other 75 sheet metal having an inherent resilient property. The casing 1, of my razor blade holder may be of any suitable shape and form that will adjustably support and secure the razor blades in a position to allow 80 men to shave with it, and while my invention contemplates any form or shape of a naked razor blade holding and supporting casing form of holder, I preferably carry out this feature of my invention in the following manner:

The casing holder comprises an outside housing or back plate portion 2, against which one side of the naked razor blade 3, is placed. This back plate portion 2, of the 90 razor blade holder is curved to fit the curve in the side of the razor blade; consequently the razor blade fits snugly up against and is firmly supported by it.

This back plate member of the holder is 95 made enough shorter than the height of the razor blade to allow the cutting edge of the razor blade to project about a thirty-second to a sixteenth of an inch above it. This razor blade supporting back plate portion 100 2, of the complete razor blade holder is provided with two projecting guide ribs 4 and 5, which are soldered or otherwise secured to it, and extend across it parallel with the cutting edge of the razor blade 3, and of the 105 upper edge of the back plate 2. The guide rib 4, is placed close to the top edge of the back plate 2, and projects preferably but a little beyond its surface. The guide plate 5, however, is placed to the lower edge of the 110 back plate and projects farther from it than the rib 4. The object of these ribs is to pro-

vide very narrow edges on the back plate to engage the face and neck, and at the same time to provide the proper shaving angle to the edge of the razor.

5 The finger grasping part of my razor blade holder comprises a short plate that is bent upon itself to form a base plate part 6, and a top razor blade clamping part 7. This razor blade holder is only long enough 10 to be held by the fingers in position to move the razor blade over the face. The bottom portion 6, contains a slight rounded corner part 8, and is provided with an upwardly projecting short tongue member 9, that is 15 cut out of the base plate and turned up above the base plate to confine the heel or bottom edge portion 10, of the razor blade against the back plate 2.

The base plate 6, of the holder, extends 20 from the seat 10^A, in a flat slightly concaved curve to the corner 8, from which it is inclined upwardly for a short distance to its terminal end, where it is bent upon itself into a small curved end 11, which forms the 25 front terminal end of the razor blade holder. From this end 11, the plate extends in the top portion 7, which I call the razor blade clamping plate, and which extends to and bears against the razor blade, with a 30 strong resilient pressure.

The razor blade 3, and its supporting back portion 2, is purposely positioned at a slight upward angle to the substantially flat base plate 6, from the lower end, of the back 35 plate 2, toward the front end 11, of the holder, and the top plate portion 7, is normally positioned to stand at a slight upwardly curved angle and to bear against the inside surface of the razor at a short distance below its cutting edge.

This razor blade clamping plate is arranged to be pressed and sprung down against the base plate 6, part of the holder, in order to release the razor blade from the 45 normal upward inherent resilient pressure of the clamping plate 7, and when the clamping plate is pressed down against the base plate 6, the razor blade is not only released, but owing to its inwardly inclined 50 position, it will fall over on top of the clamping plate, and can be picked up and removed from the holder.

In order to accommodate the holder to blades as they grow narrower from stroping, and also enable the holder to receive and support razor blades that may be narrower than the full width of blade the holder is made for, I provide the underside of the seat portion 10^A of the holder with 60 set screws 12, which can be turned to raise or adjust the height of blades and of their cutting blades as desired, relative to the upper edge of the back plate 2.

In Fig. 3, I illustrate a slight modification 65 of the shape and form of the holder

that affects the form of the razor blade's seat 10^A, the back plate, and the base plate 6, of the holder. In this arrangement, the tongue 9, is dispensed with and the corner portions of the base plate are cut into at 70 an angle 14, and the tongue members 15, which are freed by these angular cuts, are bent upwardly to stand closely against the inside curved surface of the razor blade, the tongue members being slightly curved to fit 75 into the curved side surface of the razor blade.

In this form of a housing seat for the razor blades, they are pushed into their seat in the holder endwise, and both the 80 back plate 2, and the tongues 15, are formed and arranged so that the razor blades fit snugly and slidably between them and tight enough to prevent accidental displacement. Inasmuch as in this arrangement of the 85 razor blade's seat, the razor blade must be inserted and pushed in endwise, one end of the holder may be provided with an end closing or stop portion 16, which may be a part of the back 2, as in Fig. 5, or of the 90 seat part 10^A, of the holder, as in Fig. 6.

In Fig. 7, I illustrate another modification of the razor blade housing and fastening mechanism. In this arrangement, there is a loose razor blade housing plate 17, that 95 is placed opposite the back plate 2, and that fits up against the inside surface of the razor blade, and that extends transversely across the width of the holder, and is preferably almost, but not quite, as high as the 100 back 2. This loose housing plate is pivotally secured to the base plate 6, close to its seat 10^A, in any suitable manner. I preferably, however, pivotally secure it to the base plate by means of two depending lips 105 18, that are formed on its lower edge, which extend loosely through two apertures 19, formed through the base plate, and are curved around the bottom surface of the base plate, loosely enough to allow this inside 110 housing plate to pivotally swing in the aperture up against and away from the inside surface of the razor blade. This loose housing plate is engaged by and moved and is held against the inside surface of the razor blade 115 by the upward resilient pressure of the clamping plate 7 of the holder, as shown in Fig. 7. This construction, however, is again somewhat changed in Fig. 8, where the end 20, of the clamping plate is turned downwardly to 120 strike this inside housing plate about midway of its height, and in this arrangement, the back housing plate 2, is preferably given a greater inwardly inclined angle and the clamping plate is arranged to be forced upwardly against the loose inside housing member by a screw 21.

I preferably employ a finger operated screw 21, which is threaded into the base plate and extends through it and up against 130

the underside of the clamping plate 7. This form of holder, with the ribs on the back plate and also with the razor blade raising screw and with the guards on the opposite ends of the holder, allows the razor blade, when the loose inside housing plate is released, to fall over on top of the clamping plate, and when its front edge is down against the base plate end, the razor blades are dropped sidewise into the holder between the stationary back, and the loose housing plate, and is clamped there either by the resilient tension of the clamping plate 7, as in Fig. 1, and Fig. 2, or the clamping plate is forced against the loose plate to clamp the razor blade tightly between it and the back plate by the finger operated screw.

My invention provides a finger grasping razor blade holder in which a razor blade that can be held and applied to all of the various angles it is necessary to use a razor in when shaving, that can be held more steadily and moved quicker and with safety, than the razors in common use, and while I have illustrated and described the preferred construction of my invention, I do not wish to be limited to it, as changes may be made without departing from the spirit of my invention.

When shaving down or crosswise on the face, the razor is preferably held as shown in Figs. 1, 3, 4, 5, 6, 7, 8 and 9, but when shaving up, as on the neck, it is preferably held as shown in Fig. 2; and it is preferably held as shown in Fig. 2 to insert or remove a razor blade in the holder; and it is laid down on a table or shelf preferably as shown in Fig. 2, that is, with the razor blade edge upward.

Having described my invention, what I claim as new and desire to secure by Letters Patent, is:

1. In a finger grasping razor blade holder, a razor blade and a suitable finger grasping plate form of holder for securing said razor blade in shaving positions, said holder being provided with means including a bottom and back conforming housing for securing the razor blade against displacement therefrom, said means including a stationary back plate member against which the razor blade rests, said back member being provided with ribs on its outside surface arranged to define the shaving angle of the razor blade, and a flat base portion against which the bottom or heel edge of said razor blade bears, said finger grasping portion comprising a thin bottom plate portion extending laterally from the said heel portion of said holder a short distance, and then being bent in a small curve upon itself, and extended forwardly in a resilient top plate portion to close to the razor blade, slots

through the bottom flat portion of said holder, a loose housing plate bearing against the inside surface of said razor blade and provided with lugs extending through the slots in said bottom plate, and pivotally bent up against said bottom plate and arranged to allow said plate to be moved against said razor blade, the adjacent end of said top plate member of said holder being arranged to bear against said loose housing plate with a resilient tension and arranged to clampingly hold said razor blade against said stationary back, a screw threaded through the bottom plate of said holder and bearing against the underside of said resilient top plate for forcing said top plate against said pivotally swinging plate.

2. In a finger grasping razor blade holder, a razor blade and a suitable finger grasping plate form of holder having a fixed bottom plate portion and a resiliently swinging top plate portion, said holder being provided with means, including a housing, for securing the razor blade against displacement therefrom, said means including a stationary back plate against which the razor blade rests, for securing said razor blade in said holder, said holder comprising a base plate provided with a free end plate member arranged to engage and to hold said razor blade against said stationary back plate, said free ended plate member being provided with a resilient tension and arranged to clampingly hold said razor blade against said stationary back plate, means including projecting ribs on said stationary back plate, arranged to define the shaving angle of said razor blade, means including a pivotally swinging plate for housing the inside surface of said razor blade, and a screw for forcing the free ended clamping plate against said pivotally swinging plate, and means including set screws in the bottom of said base plate for raising said razor blade in said holder, said holder comprising a casting having a base member turned upon itself to form a free end member, said base plate member being provided with a back plate portion in which a naked razor blade rests, and said free end member being formed to extend to said razor blade and arranged to clamp it to the back portion of said base plate by its inherent resilient tension, and means including free end portions cut from the opposite corners of said base plate for providing housing members for the razor blade opposite to said back plate.

In testimony whereof I affix my signature in presence of two witnesses.

JOHN A. WILLIAMSON.
